UNITED STATES PATENT OFFICE

WILLIAM E. LEWIS, OF WEST MYSTIC, CONNECTICUT

NAUTICAL INSTRUMENT

Application filed March 23, 1928. Serial No. 264,196.

My invention relates to nautical instruments for indicating direction and distance between two points of a chart.

An object of the invention is to provide a chart or map holder whereby any one of a plurality of maps or charts may be exposed for use, together with an instrument for indicating direction and distance between points on the exposed map.

10 Further the invention provides a nautical instrument which may be readily adjusted to the present location of the ship and a predetermined point on the map, and thus readily indicate the nautical mileage between 15 such points.

The invention also contemplates an instrument of this character whereby the maps or charts are enclosed and are at all times retained in a smooth condition.

20 With the preceding and other objects and advantages in mind, the invention consists in the novel combination of elements, constructions and arrangement of parts to be herein-after specifically referred to, claimed and 25 illustrated in the accompanying drawings, wherein:

Figure 1 is a top plan view of the invention;

Figure 2 is a side elevation of the same; 30 Figure 3 is a longitudinal sectional view taken on line 3—3 of Figure 1;

Figure 4 is an enlarged longitudinal sectional view taken on line 4—4 of Figure 1;

Figure 5 is a horizontal sectional view 35 taken on line 5—5 of Figure 4;

Figure 6 is a vertical sectional view taken on line 6—6 of Figure 4;

Figure 7 is a fragmentary detail view 40 partly in section and partly in elevation of the longitudinally movable carriage embodied in the invention;

Figure 8 is a fragmentary detail view partly in section and partly in elevation illustrating one of the map carrying rollers 45 and its mounting;

Figure 9 is a similar view taken at right angles to Figure 8;

Figure 10 is a sectional detail view of the casing mounting embodied in the invention; 50 and

Figure 11 is a similar view taken at right angles to Figure 10.

Referring to the invention in detail a relatively flat substantially rectangular casing 5 having a hinged top 6 is provided, the latter having a glass or window 4, which extends substantially the entire area of the top. The casing 5 is supported from a vertical bracket 7 having spaced bearings 8 at its upper end which receive a fixed horizontal pivot 9 about which a socket 10 is horizontally adjustable, the pivot 9 being held against rotation by a key 11 engaged with the bracket and pivot. The socket 10 is bifurcated at its lower end to afford a pair of clamping jaws 12 which are held in clamped engagement with the pivot by an adjusting screw 13 passing transversely through the jaws and having threaded engagement therewith. It will be observed that the socket may be adjusted to any desired point about a horizontal axis and held in this position through the medium of the clamping jaws.

To permit the casing to be swung to any selected position about a vertical axis, a plate 14, secured to the under face of the casing centrally thereof and carrying a central vertical pivot 15 revoluble in the socket, is provided. This socket is bifurcated longitudinally at one side to afford parallel laterally projecting ears 16, which are engaged by adjusting screw 17, to draw the walls of the socket against the pivot 15 to hold the casing in adjusted position about its vertical axis.

85 A longitudinally flexible sheet 18, containing a series of maps or charts, is movable longitudinally of the casing beneath the glass 6 and is adapted to be wound from one roller 19 onto another, arranged transversely of the casing at the ends thereof. These rollers are removably supported in pairs of transversely aligned U-shaped bearings 20 formed on the upper ends of vertical brackets 21, extending from the bottom wall of the casing.

90 Cooperating with each of the rollers in rotating the same to advance the sheet through the casing, is a pair of stub shafts 22 journaled in the side walls of the casing in longitudinal alignment with the rollers and pro-

jecting into axial recesses 23 in the ends thereof. The ends of the rollers are detachably coupled to the stub shafts by removable pins 24 passing transversely through the ends of the rollers and slots 25 in the ends of the stub shafts. To normally hold the stub shafts against longitudinal movement where the slots 25 will interlock with the pins 24, resilient latch elements 26 extending at right angles to the stub shafts are fixed to laterally extending brackets 27 attached to the inner face of the side walls of the casing, and at their free ends carry ears 28 which engage in circumferential grooves 29 in the stub shafts. When it is desired to remove the rollers, it will only be necessary to raise the resilient latch elements 26 to disengage the pins 28 from the circumferential grooves and the stub shafts slide outwardly from the casing. At their outer ends the stub shafts carry disks 30, one of each pair of which is provided with an actuating handle 31 whereby either one of the rollers may be rotated to advance the longitudinal sheet in the desired direction.

In order to hold the exposed area of the sheet against the under face of the glass, and to retain the sheet against accidental longitudinal displacement, a clamping plate 32 is arranged within the casing beneath the glass and carries pairs of downwardly projecting stems 33 at its ends slidably engaged within vertically disposed sleeves or sockets 34 extending from the bottom of the casing. Expansible coil springs 35 encircling these stems engage the upper ends of the sleeves or sockets and the under face of the plate to normally urge the latter into frictional contact with the exposed area of the sheet.

To determine the nautical mileage between a predetermined point upon the map and the present location of the ship and the polar direction of such predetermined point, a combined protractor and direction indicator is provided. The protractor and direction indicator comprises a pair of longitudinally extending guide bars 36 secured to the upper face of the casing adjacent its opposite longitudinal edges and spaced from the casing by upstanding bosses 37 to which the bars are attached by fastenings 38. A carriage comprising rectangular sleeves 39, slidable on the guide bars and connected by parallel guide bars 40 extending transversely of the casing, is longitudinally movable of the latter. Each of these guides 39 is provided with a removable side plate 41 held in place by removable fastenings 42. The inner face of each of the plates is provided with an elongated recess 43 in which a corrugated leaf spring 44 is arranged, the latter engaging the guide bars 36 to hold the carriage in adjusted position.

A horizontal plate 45 is arranged between

the guide bars and carries rectangular sleeves 46 at its ends, slidably received on the guide bars 40, to permit the plate to be adjusted transversely of the casing. The sleeves 46 are also provided with removable plates 45' 70 which carry leaf springs 46' identical to the springs 44 and which engage the guide bars 40. An upstanding split clamping collar 47 projects centrally from the upper face of the plate 45 with which it is integrally associated, and encircles a hollow shaft 48 passing through the plate and depending below the same, as particularly illustrated in Figure 6. The split collar 47 is of a greater diameter than the hollow shaft, and embraces 75 an annular flange or ring 48' projecting centrally from the under face of a compass-rose or dial 49, the compass-rose and annular flange being rotatably received on the hollow shaft. Lateral ears 50 project from the free edges of the split collar 47 and are engaged by a horizontally disposed hand operated screw 51 for the purpose of drawing the clamp into such frictional engagement with the annular flange as to prevent 80 free rotation of the compass-rose. An indicating hand 54 is carried by the upper end of the hollow shaft and is movable over the graduations on the compass-rose. A second split collar 51a depends from the under face 95 of the plate 45, through which the hollow shaft passes. Lateral ears 52 are provided on the collar 51a and are engaged by an adjusting bolt 53 whereby the collar may be drawn sufficiently tight against the hollow 100 shaft as to prevent free rotation of the latter.

A horizontally disposed protractor arm 55, having one end fixed to the lower end of the hollow shaft, is provided, and normally lies in close relation to the glass and exposed map beneath the same. This protractor arm is graduated in nautical miles and is adapted to be swung to any desired point over an exposed map with the shaft 110 48 as its axis.

The operation of the invention is as follows: The compass-rose is first adjusted to dispose its center (the hollow shaft 48) directly above the point of present location on the map. This is accomplished by adjustment of the carriage longitudinally of the casing and the compass-rose transversely thereof, and sighting the map by looking through the hollow shaft. With the compass-rose thus positioned over the point of present location the protractor arm is swung to a position where it intersects the center of the compass markings C which are provided on each of the charts or maps on the sheet 120 18. The compass-rose is now rotated to dispose its markings or indicia in the same relation to the map as the compass marking C.

To find the nautical mileage and polar direction of a predetermined port, it is now 130

only necessary to swing the protractor arm to the dotted line position to intersect the port designated at X. The distance in nautical mileage may be readily ascertained by observing the graduations on the protractor arm from the compass-rose to the port of destination. By reason of the indicating hand 54 being fixed to the hollow shaft 48 the protractor arm and indicating hand will move together. Thus with the protractor arm lying in the dotted line position, the indicating hand will lie in the dotted line position and indicate the direction of the port of destination.

15 It will be observed that it will be only necessary to adjust the compass-rose to correspond to the compass marking C of each map. That is to say, after the compass-rose is adjusted it will remain in such adjustment until another map has been brought into position for use.

What is claimed:—

An apparatus of the character described including a base, a carriage slidably mounted 25 on the base, a plate longitudinally adjustable on the carriage, a tubular member extending through the plate and rotatably supported thereby, a compass-rose revoluble with one end of the tubular member and having a 30 depending circular flange surrounding said end, a protractor arm carried by the opposite end of the tubular member, split collars extending from each face of the plate respectively, one of said collars embracing the 35 tubular member and the other of said collars embracing said circular flange, and means co-operating with each of the collars for causing the same to frictionally engage the tubular member and flange respectively.
